UNITED STATES PATENT OFFICE.

FRIEDRICK BRITSCH, OF NEW YORK, N. Y.

DESIGN FOR GALLOON.

SPECIFICATION forming part of Design No. 23,133, dated March 20, 1894.

Application filed February 5, 1894. Serial No. 499,206. Term of patent 7 years.

To all whom it may concern:

Be it known that I, FRIEDRICK BRITSCH, a citizen of the United States, residing at New York, in the county of New York and State 5 of New York, have invented a new Design for Galloon, of which the following is a specification.

The leading feature of this design for galloon, consists in the design of the heavy 10 transverse ribs in the central part with intermediate small transverse cords and top and bottom stripes having heavy raised cords resembling alternating diamond shaped figures.

In the drawings:—Figure 1. is a representation 15 of the design for galloon flatwise, and Fig. 2. is a representation edgewise.

The edges *a* of the furniture galloon are scalloped as usual. The center stripe contains the heavy projecting transverse ribs *b*, and small intermediate transverse cords *c*, 20 and the heavy cords in the top and bottom stripes *d*, *e*, have the appearance of small alternating and raised diamond-shaped figures.

I claim—

The design for a galloon as herein shown 25 and described.

Signed by me this 31st day of January, 1894.

FRIEDRICK BRITSCH.
